UNITED STATES PATENT OFFICE

VINCENT PAUL PARCHEN, OF CHICAGO, ILLINOIS, ASSIGNOR OF ONE-HALF TO ALBERT H. KOLKER, OF CHICAGO, ILLINOIS

COMBINED MONEY BANK AND ARTICLE HOLDER

Application filed June 10, 1929. Serial No. 369,876.

This invention relates to a device serving the combined purpose of a money bank and a holder for an article of frequent use, access to which can be attained only by the insertion of money into the bank.

The object of the invention is to provide an improved construction of such a device, and one which, while being very reliable in service and convenient in use, can be made very economically.

The invention proceeds upon the principle of having, in a money bank, an extra compartment in which may be placed an article of daily use, for instance, a shaving outfit or other toilet article, and having the closure for such holder and the slot through which money is introduced into the bank so related and connected by locking mechanism that insertion of money through the slot will act upon the locking mechanism to release the closure; the closure and the slot being located in one and the same wall of the bank; the locking mechanism comprising a pair of pivoted levers having their ends associated in pairs, with one pair of ends presented in the path of the money introduced through the slot, and the other pair of ends arranged in dogging relation to the closure. In its preferred form, the invention contemplates the use of a sliding tray as the holder; an arrowhead keeper on said tray through the medium of which the locking mechanism enters into dogging relation with the tray; the crossing of the two levers at a common fulcrum point; and the deflecting of the ends of the levers to provide projections through which said ends, respectively, coact with the deposited money and with the tray-like closure.

In the accompanying drawings—

Figure 1 is a perspective view of a combined bank and article holder with the closure or tray in open position.

Figure 2 is a section of the same in a vertical longitudinal medial plane indicated generally by the section line 2x—2x in Figure 1.

Figure 3 is a section in a medial transverse plane with the tray closed.

Figure 4 is a horizontal section on the line 4x—4x of Figure 3.

Figure 5 is a section on the line 5x—5x of Figure 3; and

Figure 6 is a section on the line 6x—6x of Figure 5.

1 represents the money bank which, for the purpose of giving access to its money compartment 2, is preferably constructed with a removable top 3 secured in some suitable manner, such, for instance, as by tongue and groove engagement 4 (Figure 2) at one end of the bank, and a key controlled lock 5 at the other end thereof. Beneath the money compartment 2 the bank has a compartment 6 which is adapted to serve as an article holder, preferably through means of a tray 7 fitted therein. This tray 7 is adapted to be intruded into the compartment 6 in opposition to ejecting spring 8 until the front 9 of the tray becomes flush with the front wall 10 of the bank, in which position the tray will be automatically latched through the medium of the arrowhead or equivalent keeper 11 interengaging with a pair of dogs 12 (see Figures 1 and 5). Locking dogs 12 are provided by the inturned lower ends of a pair of levers 13 crossed and mounted upon a common fulcrum pin 14, and having their upper ends 15 presented in the path of money introduced through the slot 16 in the front wall 10 of the bank. Levers 13 are normally drawn together by spring 17 to yieldingly hold their dogging ends 12 and money controlled ends 15 in effective position; and the money controlled locking mechanism thus provided is mounted upon the same wall of the bank in which the slot 16 is formed and the closure 9 is fitted; said mounting being effected through the medium of a lock case 18 mounted on the inner face of said wall 10. The pair of ends 15, as shown in Figure 6, may be provided with one or more sharp edges to resist retracting a coin that has once been started through the slot.

From the foregoing description it will be seen that the invention contemplates a pair of pivoted levers having their upper and lower ends related in pairs, for the purposes stated, and mounted upon the same wall 10

in which are provided the deposit slot 16 and the compartment closure 9; also that the levers extend from the slot which is in the upper portion of the wall to the closure which is in the lower portion thereof, and as shown in Figure 3, this arrangement affords a very compact, simple, and reliable mechanism occupying minimum space within the money compartment.

10 I claim:

1. A combined money bank and article holder constructed with a deposit slot, a relatively movable article compartment adapted to support an article, and pivoted locking levers having their ends related in pairs; one pair of ends being presented in the path of money deposited through said slot; the other pair of ends being arranged in dogging relation to said closure, the locking levers having 15 their ends that are presented in the path of the money, deflected each toward the other, and constructed to provide a ratchet to resist return movement of money started through the slot.

2. A combined money bank and article holder constructed with a deposit slot, a relatively movable compartment adapted to support an article, means for locking said compartment against moving, and means operated by a coin as it passes through said slot to cause an unlocking of said compartment, said last mentioned means including ratchets shaped to resist a reversal of movement of 20 a coin.

3. The combination with a drawer adapted to support an article of frequent and regular use, of pivotal levers for locking said drawer, said levers including a related pair of ratchet portions and being arranged to 25 be swung apart by the passage of a coin between said ratchet portions, a spring for thereupon opening said drawer, and cam means on said drawer arranged to again spread said levers apart upon the closing of 30 said drawer to release a coin caught more than halfway past said ratchet portions.

4. A combined money bank and article holder constructed with a deposit slot, a movable closure, means for locking said closure against movement, and means operated 35 by the coin as it passes through said slot to cause an unlocking of said closure, said last mentioned means including ratchets shaped to resist a reversal of movement of 40 the coin.

Signed at Chicago, Illinois, this 5th day of June, 1929.

VINCENT PAUL PARCHEN.
